CLAIM

The ornamental design for a toy launcher, as shown and described.

DESCRIPTION

FIG. 1 is a front perspective view of the toy launcher of the present invention showing my new design and an opened compartment;

FIG. 2 is front side elevational view thereof;

FIG. 3 is a back side elevational view thereof;

FIG. 4 is a side elevational view thereof;

FIG. 5 is another side elevational view thereof;

FIG. 6 is a top plan view thereof; and,

FIG. 7 is a bottom plan view thereof.

The broken lines in the drawings represent portions of the toy launcher that form no part of the claim.

1 Claim, 5 Drawing Sheets
